UNITED STATES PATENT OFFICE.

JOHN SIGFRIED KENDALL, OF HAMILTON, ONTARIO, CANADA.

ROTATING SIGN.

1,106,148.

Specification of Letters Patent.

Patented Aug. 4, 1914.

Application filed December 15, 1913. Serial No. 806,817.

To all whom it may concern:

Be it known that I, JOHN SIGFRIED KENDALL, of the city of Hamilton, in the county of Wentworth, in the Province of Ontario, 5 Canada, have invented certain new and useful Improvements in Rotating Signs, of which the following is the specification.

My invention relates to improvements in rotating signs, and the object of the invention is to devise a sign which will intermittently rotate and disclose different advertisements to view; a further object is to construct a sign in which the advertisements will be illuminated and also to provide 15 means for throwing the lamp out of circuit when the sign is rotating.

The invention consists of a wheel carrying the advertising signs, means for driving the wheel from an electric motor or other source 20 of power, brackets extending outwardly from the periphery of the aforesaid wheel, means connected to the driving means for engaging the brackets when they are in a certain position, said means being designed 25 to be released from engagement with the brackets when the wheel has been rotated a requisite extent, and means for electrically connecting a lamp mounted on the aforesaid wheel to an electric light circuit where- 30 by the lamp is adapted to be lighted when an advertising sign is in position and to be out when the sign is being rotated, said wheel being mounted eccentrically of the said driving means, all as hereinafter more 35 particularly described and illustrated in the accompanying drawing, in which:—

Figure 1 represents a side elevation of a sign constructed according to my invention. Fig. 2 is a plan view thereof. Fig. 3 is a 40 perspective view of one of the brackets showing contact fingers adapted to connect the lamp with an electric light circuit and Fig. 4 is an elevation of a portion of the sign showing a modified form. Fig. 5 is a 45 diagrammatic view of the electrical connections between the lamp and the electric light circuit. Fig. 6 is a perspective detail of a roller pivotally mounted on a pin connected to the driving means, said roller being 50 adapted to engage the aforesaid brackets.

Like characters of reference indicate corresponding parts in the different views.

1 is the frame of the sign which in the present instance is divided into four sections 2 constructed of transparent material and 55 adapted to carry advertising matter.

3 is a wheel freely mounted on the vertical shaft 4. 5 is an electric lamp socket suitably mounted on the said wheel and 6 is an electric lamp bulb. 60

7 is a motor.

8 is a fixed vertical shaft mounted on the bracket 9.

10 is a large pulley wheel freely mounted on the shaft 8 and 11 is a small pulley wheel 65 keyed to the motor shaft.

12 is a belt connecting the pulley wheel 10 with the pulley wheel 11.

13 is a small pulley wheel mounted on the top of the aforesaid pulley wheel 10, and 70 consequently free of the shaft 8.

14 is a vertical fixed shaft mounted on the bracket 15.

16 is a pulley wheel freely mounted on the shaft 14, and 17 is a small pulley wheel 75 connected thereto and consequently free of the shaft 14.

18 is a belt connecting the pulley wheels 13 and 16 together.

19 is a large pulley wheel freely mounted 80 on the shaft 8 above the aforesaid pulley wheels 10 and 13, and 20 is a belt connecting the pulley wheel 19 with the pulley wheel 17.

21 is a bracket rigidly connected to the fixed shaft 8 and carrying the shaft 4 with 85 which it is rigidly connected, it being understood that the wheel 3 is freely mounted on the shaft 4 as above stated.

22, 22 are outwardly extending brackets or plates secured to the wheel 3 and carrying the plates 23 constructed of suitable insulating material. 90

24, 24 and 25, 25 are upper and lower contact fingers respectively attached to the brackets 22 by the bolts 26 and insulated 95 therefrom by the plates 23 and 27.

28 is a vertical bracket carrying the upper and lower contact fingers 29 and 30, said contact fingers being either insulated from the said bracket 28 or the said bracket being 100 constructed of insulating material. The contact fingers 29 and 30 are connected to the wires 31 and 32 which are in turn connected to an electric light circuit.

33, 33 are wires connecting the lower contact fingers 25 with one of the terminals of the lamp 6, and 34, 34 are wires connecting the upper contact fingers 24 with the other 5 terminal of the lamp.

35 is an upwardly extending vertical pin suitably mounted on the rim of the pulley wheel 19, and 36 is a horizontal roller pivotally mounted on the top of said pin.

10 From the above description it will be seen that the wheel 3 is eccentrically mounted in relation to the pulley wheels 10 and 19 which are mounted on the shaft 8.

In the modification shown in Fig. 4 a 15 small casing 37 is mounted on the wheel 3 and is provided with a series of lenses 38 carrying the advertising matter, it being understood that the casing 37 surrounds the lamp 6 and the letters of the advertisement 20 are adapted to be projected on to a ground glass filling the aperture in the inclosing casing.

The operation of the device is as follows:—When the sign is in the position 25 shown in Fig. 1 or Fig. 2, the lamp 6 is lighted as the contact fingers 24 and 25 are in engagement with the contact fingers 29 and 30 respectively, which as above described are connected to the electric light 30 circuit by the wires 31 and 32, but as will hereafter be apparent the lamp 6 goes out when the sign is rotated and does not light again until the next set of contact fingers 24 and 25 come into contact with the contact 35 fingers 29 and 30. Further it is to be understood that the motor circuit is an entirely separate circuit from the electric light circuit and when the current is turned on and the motor revolved the pulley wheel 10 40 freely mounted on the shaft 8 will be revolved, as it is connected to the motor pulley 11 by the belt 12. The pulley wheel 13 which is connected with the pulley wheel 10 will also be revolved and consequently 45 the pulley wheel 16 which is connected thereto by the belt 18. As the pulley wheel 17 is mounted on the pulley wheel 16 this will also be revolved and consequently the upper pulley wheel 19 which is connected to the 50 pulley wheel 17 by the belt 20 will be revolved. As will be apparent the reason for using the above arrangement is to reduce the speed of the pulley wheel 19 in relation to the motor pulley wheel 11, and when the 55 roller 36 comes into the position shown in Fig. 2 it will engage a bracket 22 on the wheel 3 and will thus revolve this wheel until the bracket comes into position at right angles to its initial position when the roller 60 will roll off the bracket and consequently allow the wheel to stop. It will be seen that this will take place, as the wheel 3 is eccentrically mounted in relation to the pulley wheel 19. Now when this movement takes

place a set of contact fingers 24 and 25 will 65 come into engagement with the contact fingers 29 and 30 and the lamp 6 will be lighted again, thus disclosing the advertisement. After the roller has been released from the bracket it will not engage another bracket 70 until the pulley wheel 19 has made three-quarters of a revolution when the roller 36 will again come into the position shown in Fig. 2 and will engage the next bracket, consequently the lamp will be lighted and 75 each advertisement will appear for a certain time.

It is to be understood that the device can be arranged so that the sign will either operate more quickly or more slowly as is 80 shown in the present instance. Further any number of signs can be constructed and the device arranged and timed so as to show each in turn.

What I claim as my invention and desire 85 to secure by Letters Patent is:—

1. In a rotating illuminated sign the combination with means for carrying advertisements, of a wheel supporting the advertisement carrying means, a lamp within the advertisement carrying means, radially extending brackets secured to the wheel and extending exteriorly of the periphery thereof, an electric light circuit, pairs of contact fingers mounted on each of the brackets and 90 insulated therefrom and from each other, said contact fingers connected to the lamp, a pair of contact fingers connected to the electric light circuit, said contact fingers insulated from each other said first mentioned 100 pair of contact fingers being adapted to contact with said last mentioned pairs of contact fingers, a second wheel rotatably mounted below the aforesaid supporting wheel, said supporting wheel situated eccentrically of 105 the second wheel, means for rotating the second wheel, and means connected to the second wheel for engaging each bracket in succession for a predetermined time for rotating the supporting wheel a requisite extent. 110

2. In a rotating illuminated sign the combination with means for carrying advertisements, of a wheel supporting the advertisement carrying means, a lamp within the advertisement carrying means, radially extending brackets secured to the wheel and extending exteriorly of the periphery thereof, an electric light circuit, pairs of contact fingers mounted on each of the brackets and 115 insulated therefrom and from each other, said contact fingers connected to the lamp, a pair of contact fingers connected to the electric light circuit, said contact fingers insulated from each other said first mentioned pair of contact fingers being adapted to 120 contact with said last mentioned pairs of contact fingers, a second wheel rotatably mounted below the aforesaid supporting 125

wheel, said supporting wheel situated eccentrically of the second wheel, means for rotating the second wheel, and a vertically extending pin mounted on the second wheel, a horizontal roller rotatably mounted on the top of the pin and engaging in succession the respective brackets.

In testimony whereof, I have signed at

the city of Hamilton, in the county of Wentworth, in the Province of Ontario, Canada, 10 this 3rd day of December, 1913.

JOHN SIGFRIED KENDALL.
